Primary Examiner — T Chase Nelson*Assistant Examiner* — Yuan Yuan(74) *Attorney, Agent, or Firm* — Vladimir Postnikov(57) **CLAIM**

The ornamental design for a fidget cube, as shown and described.

DESCRIPTION

FIG. 1 is a top-front-left perspective view of a fidget cube, showing my new design;

FIG. 2 is a bottom-rear-right perspective view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a left-side elevation view thereof; and,

FIG. 8 is a right-side elevation view thereof.

The broken lines depict portions of the fidget cube that form no part of the claimed design.
